UNITED STATES PATENT OFFICE.

JEFFERSON P. JONES, OF WALDRON, ASSIGNOR TO GEORGE W. HILE AND
FREEMAN C. MASON, BOTH OF RANSOM, MICHIGAN.

PERMUTATION-LOCK.

SPECIFICATION forming part of Letters Patent No. 416,629, dated December 3, 1889.

Application filed May 28, 1888. Serial No. 275,336. (Model.)

To all whom it may concern:

Be it known that I, JEFFERSON P. JONES, a citizen of the United States, residing at Waldron, in the county of Hillsdale and State of Michigan, have invented certain new and useful Improvements in Locks; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to combination or permutation locks, and has for its object the provision of a lock of this nature which cannot be opened by feeling and sound, and in which the combination can be changed as often as may be desired without the necessity of having to remove the tumblers from their shaft. The bolt-locking lever is weighted at its outer end and its inner end is normally held off from the tumblers—that is, it does not rest or ride on the tumblers—and if caused to bear upon the tumblers by operating the knob-shaft the tumblers cannot be moved only a limited distance because of the stops provided on their periphery engaging with the said lever. The locking-lever is operated by a lifting-arm that is keyed to a sleeve mounted on the knob-shaft, said sleeve having a thumb-piece or head on its outer end to be grasped between the fingers for operating it. This lifting-arm serves as a supplemental means for locking the locking-bolt when the said bolt is projected.

The improvement consists of the novel features, which hereinafter will be more fully described and claimed, and shown in the annexed drawings, in which—

Figure 1 is a view of the inner side of a safe-door, showing my improved lock; Fig. 2, a vertical section on the line X X of Fig. 1; Fig. 3, a detail view of the locking-lever, the means for throwing the bolts, and the keeper on an enlarged scale; Fig. 4, a perspective view of a keeper, a tumbler, and the tumbler-shaft; Fig. 5, a detail view of the notched disk for operating the bolts; Fig. 6, a perspective view of the keeper; Fig. 7, a sec-

tional view through the knob-shaft, showing the sleeve and the lifting-arm; Fig. 8, a detail view of the inner side of the locking-bolt, showing the lifting-finger in position, and Fig. 9 shows detail views of other three tumblers.

The tumbler-shaft A and the knob a with its graduated base are of usual construction.

The tumblers B are constructed alike, and a detailed description of one will suffice for each. The tumbler is provided with a series of notches b in its periphery and a series of pins or stops b'. All of the notches save one are filled with removable blocks C, which come flush with the periphery of the tumbler. Any one of the blocks C can be removed and inserted in the vacant notch to effect a change in the combination. The pins or stops b' extend a short distance from the periphery of the tumbler to engage with the locking-lever D, if the same is caused to bear against the tumbler and prevent a free movement of the said tumbler except in the space between two of the said pins or stops, thereby preventing the feeling of the lock by unauthorized persons to ascertain the combination. The central opening of the tumbler is larger than the tumbler-shaft and receives the tubular extension of the keeper E, on which the tumbler is mounted. The side of the tumbler is provided with the recess b², within which the arm a', projecting from the tumbler-shaft, works and is adapted to strike the stop b³, projecting from the wall of the recess b², to move the said tumbler when rotating the shaft A. When the tumblers are arranged in series, the distance between the sides of the stop will vary for each tumbler. This variation is effected in one of two ways—either by widening the stop b³ or providing a second stop b⁴, which is placed at different distances from the stop b³. The first tumbler of the series has the greatest movement relative to the shaft A, and the last tumbler of the series the least movement, and the intermediate tumblers of the series a movement proportionate between these two extremes.

The keepers E conform to the size of the tumblers and have notches e', which coincide with the notches in the tumblers, the notches e' being in a straight line to receive the end

of the lever when the notches in the tumblers are in alignment. The ears e^2 , projecting from the edges of the keepers are thickened or provided with the lugs e^3 on their rear sides, which space the keepers apart to permit the tumblers to work freely between each two of the keepers without any binding. The lugs and the ears are perforated and the bolts b^4 , passing through the perforations, bind the keepers together and secure them to the door. The tumbler-shaft has a bearing in each of the keepers and the tumblers are mounted on the tumbler-extensions of the keepers.

15 The main locking-bolt F is centrally disposed and is provided with the upper and the lower arms f and f' , which engage with the upper and the lower locking-bolts G and G' , respectively, the ends of the arms fitting in notches in the edges of the said bolts G and G' , so that in the event of the main bolt being displaced the arms will disengage themselves from the bolts G and G' , which will remain projected and hold the door shut. The stud f^2 , projecting from the bolt, fits in a notch in the disk H , which is mounted on the knob-shaft I and turns with the said shaft.

30 The front end of the locking-lever D is weighted and rests on the bolt F , and drops in the notch f^3 in the said bolt F to lock it when projected. This lever is disengaged from the bolt F by the lifting-arm k , which is keyed to the sleeve K , mounted on the knob-shaft, the outer end of the sleeve having the head or thumb piece k' , which is grasped between the thumb and fingers to rotate the sleeve and elevate the arm k and lever D . The arm k fits in a recess f^4 in the bolt F when the bolt F is projected, and in 40 connection with the lever D holds the bolt projected.

45 The vertical bolts L and M overlap or extend across the bolt F , and have projections or studs l and m , respectively, which fit in notches in the disk H . The auxiliary bolts N and O have notches which receive the ends of the rods l' and m' , which project from the bolts L and M respectively.

50 When the door to which the lock is applied is open and the several bolts are retracted, the lifting-arm k will have its end resting on the locking-bolt and the lever D will have its outer end also resting on the said bolt and its inner end fitted in the notches in the 55 keepers and the tumblers. When the bolts are projected, the end of the arm k will drop in the recess in the bolt F and the locking-lever D will engage with and lock the said bolt F . The inner end of the locking-lever D stands 60 at a sufficient distance from the tumblers to

clear the pins or stops b' thereof and permit the free movement of the tumblers in either direction.

To unlock the bolts, the tumbler-shaft A is operated in the usual manner through the 65 knob a to bring the notches in the tumblers in alignment with the notches in the keepers. Then the sleeve K is operated to elevate the end of the arm k and disengage the lever D from the bolt F . Now, by operating 70 the shaft I the bolts will be retracted and the door is free to be opened.

Having thus described my invention, what I claim, and desire to secure by Letters Patent, is—

75 1. In a combination-lock, the combination, with a tumbler having a series of notches in its periphery, of a series of removable and interchangeable blocks whereby the combination can be changed without removing the 80 tumbler from its support or shaft, substantially as set forth.

2. In a combination-lock, the combination, with the tumbler and a locking-lever, of a series of pins or stops projecting from the 85 periphery of the tumbler to engage with the said locking-lever, substantially as and for the purpose specified.

3. The combination, with the tumbler-shaft and the keepers having a tubular extension 90 and lateral ears, of the tumbler mounted on the tubular extension of the keepers, and the bolts for securing the keepers together, substantially as described.

4. The combination of the tubular shaft, 95 the series of keepers having ears, which ears are thickened at their ends and are perforated and having notches in their edges and tubular extensions, the bolts passing through the perforations in the said ears and binding the keepers together and securing them to the door, the tumblers mounted on the tubular extensions of the keepers and having recesses in their sides of varying lengths, and the arms projecting from the tubular 100 shaft and working in the said recesses of the tumblers, substantially as described.

5. The combination, with the tumblers, the locking-lever, the locking-bolt, and the knob-shaft, of the sleeve mounted on the knob-shaft, and the lifting-arm keyed to the sleeve and adapted to disengage the locking-lever from the said locking-bolt and to lock the 110 said lever, substantially as specified.

In testimony whereof I affix my signature in 115 presence of two witnesses.

JEFFERSON P. JONES.
